UNITED STATES PATENT OFFICE

154,912

DESIGN FOR A COOKING UTENSIL

Tom Elleman and Wayne C. Cather, Toledo, Ohio

Application April 15, 1947, Serial No. 138,424

Term of patent 3½ years

(Cl. D44—1)

To all whom it may concern:

Be it known that we, Tom Elleman and Wayne C. Cather, both citizens of the United States, residents of Toledo, county of Lucas and State of Ohio, have invented a new, original, and ornamental Design for Cooking Utensil, of which the following is a specification, reference being had to the accompanying drawings, forming part thereof.

In the drawings,

We claim:

The ornamental design for a cooking utensil, substantially as shown.

TOM ELLEMAN.
WAYNE C. CATHER.
